UNITED STATES PATENT OFFICE.

WILLIAM ROBERT BELL, OF NEW YORK, N. Y.

MOTOR.

SPECIFICATION forming part of Letters Patent No. 402,713, dated May 7, 1889.

Application filed February 27, 1889. Serial No. 301,330. (No model.)

To all whom it may concern:

Be it known that I, WILLIAM ROBERT BELL, of the city, county, and State of New York, have invented a new and Improved Motor, of 5 which the following is a full, clear, and exact description.

The object of my invention is to provide an inexpensive and reliable motor for light-running machines, such as sewing-machines; and 10 to the end named the invention consists, essentially, of a sleeve or shaft that is to be driven, said shaft or sleeve being formed with recesses, pawls mounted in said recesses, rings formed with internal ratchets, said ratchets being arranged so that they will be engaged 15 by the pawls, and bands connected to the rings and to a frame, all as will be herein-after more fully explained, and specifically pointed out in the claims.

20 Reference is to be had to the accompanying drawings, forming a part of this specification, in which similar figures and letters of reference indicate corresponding parts in all the views.

25 Figure 1 is a side view of my improved motor. Fig. 2 is an enlarged sectional view taken on line 2 2 of Fig. 1. Fig. 3 is a sectional view taken on line 3 3 of Fig. 2. Fig. 4 is a view on line 4 4 of Fig. 2, and Fig. 5 is a detail 30 view of one of the tightening devices.

In the drawings, 10 represents a balance-wheel, which also serves as a pulley, if desired, the driving-belt being in such case placed in the groove *e*, formed in the rim 11. 35 The wheel 10 is mounted on a stud, 12, and held from displacement by a collar, 13, and a washer, 14, that is held to the stud by a screw, *n*, the wheel-hub being formed with an extending sleeve, 15, which abuts against the 40 washer 14.

The sleeve 15 is recessed at *ff'*, and in these recesses there are mounted pawls 16 and 16^a, such pawls being supported by a pin, 17, arranged as best shown in Fig. 2.

45 Upon the sleeve 15, I mount rings 18, 19, 20, 21, and 22, the rings 18, 20, and 22 serving as spacing-rings and as supports for a frame, 30, while the rings 19 and 21 are the driving-rings and are formed with internal ratchets 50 *i i'*, that are engaged, respectively, by the

pawls 16 and 16^a, springs *k* being arranged in connection with the pawls.

The frame 30 carries four bands or cords, *a*, *b*, *c*, and *d*, the cords or bands *a b* being passed about the ring 21 in opposite directions to engage a pin, *o*, the ends of the bands or cords being looped to provide for the passage of the pin, while the bands *c* and *d* are correspondingly connected to the ring 19, the connection, however, being upon the opposite side of the 60 ring. The bands *a* and *d* and *c* and *b* extend about their rings in the same direction. It will be noticed that the pawls 16 and 16^a point in the same direction.

In order that the frame 30 may be reciprocated, I connect it with a treadle, 31, as shown in Fig. 1.

If the treadle be moved as indicated by the arrow, the frame 30 will be drawn downward and the cord or band *b* will draw its ring 21 70 in the direction of the arrow shown in Fig. 3, and the ring so moving would advance the wheel 10, inasmuch as the pawl 16 would be engaged by the ratchet *i'*. As the frame 30 is moved downward, as just described, the 75 cord *d* would draw on its ring 19 and such ring would be moved, as indicated by the arrow marked *x* in Fig. 4; but when the frame 30 is moved upward the cord *c* would draw on the ring 19 and the ring would be carried in 80 the direction of the arrow marked *y*.

From the above description it will be seen that when the frame moves downward the ring 21 drives the wheel 10, while the ring 19 slips over its pawl, and that when the frame 85 moves upward the ring 19 drives the wheel 10 and the ring 21 slips, and it will also be seen that an exceedingly slight movement of the frame will act to drive the wheel.

In practice I prefer that the bands *a*, *b*, *c*, *d* should be made of steel, and in such case I connect the bands at one end of the frame to hooks, as *p*, and at the other end of the frame to clamps *r*, having threaded shanks *s*, that are engaged by winged nuts *t*, this arrangement being preferred in order that all undue slack may be taken up.

Although I have described my motor as being arranged in connection with a sleeve forming a portion of the driving-wheel, I desire it 100

to be distinctly understood that the motor might be arranged in connection with a shaft.

It will be noticed that the rings 18, 20, and 22 serve as supports for the frame 30, such frame being guided at one side by the wheel hub and at the other by the washer 14.

Having thus described my invention, what I claim as new, and desire to secure by Letters Patent, is—

- 10 1. In a motor, the combination, with a driven member provided with pawls, of rings formed with internal ratchets that are engaged by the pawls, bands passed about the rings in opposite directions, and a frame to which the bands are connected, as and for the purpose stated.
- 20 2. In a motor, the combination, with a driven member provided with pawls, of rings formed with internal ratchets that are engaged by the pawls, bands passed about the rings in opposite directions, a frame to which the bands are

connected, a treadle, and a connection between the treadle and the frame, substantially as described.

3. In a motor, the combination, with a driven member provided with pawls, of a ring, 19, formed with an internal ratchet that is engaged by one of the pawls, bands connected to the ring and passing in opposite direction about said ring, a frame to which the bands are connected, a ring, 21, also formed with an internal ratchet that is engaged by the other pawl, bands which pass in opposite directions about and are connected to the ring 21, the point of connection being opposite that of the ring 19, connections between the bands and the frame, and means for reciprocating the frame, as and for the purpose stated.

WILLIAM ROBERT BELL.
